MAKING SLIDE FASTENERS

George Henry Clifford Corner, Birmingham,
England, assignor to Hookless Fastener Com-
pany, a corporation of Pennsylvania

Application September 29, 1932, Serial No. 635,408
In Great Britain September 30, 1931

3 Claims. (Cl. 29—148)

This invention relates to slide fasteners of the type in which each of a pair of flexible stringers, such as fabric tape, is provided along one edge with a series of interlocking elements or teeth, called scoops, both rows of scoops passing through a slider which when moved in one direction guides them into interlocked relation to close the fastener and when moved in the opposite direction separates the teeth to open the fastener.

10 In the accompanying drawing:

Fig. 1 is a plan view of a well known type of slide fastener, with which this invention is concerned.

15 Fig. 2 is an enlarged perspective view of one of the fastener elements or scoops.

Fig. 3 shows a number of scoops assembled into a unitary structure constituting one form of my invention, and illustrates a step in the process of manufacture of the fastener.

20 Fig. 4 is an enlarged perspective view of a portion of the structure shown in Fig. 3.

Fig. 5 is a view corresponding to Fig. 4 showing a modified form.

Fig. 6 is a section on the plane 6—6 of Fig. 4.

25 Fig. 7 shows the step in the process of manufacture succeeding the step of Fig. 3.

Slide fasteners are well known having a number of scoops 20, shown best in Fig. 2, each having an asymmetrical head portion provided with a locking projection 21 designed to fit into the locking recess 22 of an adjacent scoop, and also having a base or bifurcated portion with two prongs 24 adapted to be clamped about an edge 25, usually beaded, of a flexible supporting member or tape 26 shown in Fig. 1. The two tapes, thus provided with teeth or scoops are called stringers and are secured together by a clamp or bottom stop 27 and by any suitable type of slider 28, through which both rows of scoops pass, and which serves to interlock or release the scoops, as is well known. Each of the tapes is also usually provided with a top stop 29 to prevent the slider from being removed from the stringers. The tapes are sewed to the edges of the garment or article to be closed or fastened.

45 Slide fasteners of this type have heretofore been made by first forming the scoops 20 in a forming machine and subsequently clamping them, one at a time, on the edge of the tape. The scoops must be carefully spaced along the tape in order that they may properly mesh with the scoops of the mating stringer. And if the fastener is to be perfectly satisfactory, particularly as regards ease of operation, strength, 50 flexibility and security when flexed under strain,

the attaching of the teeth to the tape and their spacing along the tape must be done with a high degree of accuracy. It will be appreciated that this requires very accurately made machines which must not only run at high speed but also maintain their accuracy and adjustment under production conditions, and are accordingly complicated and expensive.

5 Because of the machinery required, fasteners are customarily made in a properly equipped central factory where they are assembled in particular lengths and provided with the top and bottom stops before being sent to the users, such as clothing manufacturers. This, as a practical matter, requires the fasteners to be factory-made 10 to exact lengths, and makes it inconvenient for the user to alter the length of a fastener to suit his requirements.

15 One of the objects of my invention is to provide a fastener unit, readily transportable and salable as an article of commerce, which can be accurately assembled at the factory in any practical lengths, and which can be readily cut to desired lengths by the user and easily assembled into a complete fastener without expensive or complicated machinery. This permits quantities of stock to be kept on hand and used as desired in any length, instead of requiring each particular 20 length to be especially made.

25 Moreover, in providing an article or a garment with an opening closed by a slide fastener of this type, it has been necessary to attach the teeth to a tape, as above outlined, and sew the tape to the article to be used. The inclusion of this extra piece of tape may be undesirable, particularly in certain fine garments. It is accordingly one of the objects of my invention to provide a method of and means for attaching the scoops directly to the edges of a garment or other article, which may be practically and conveniently practiced on 30 a commercial scale.

35 In practicing my invention, scoops are arranged with the bifurcated portions in alignment and the humps 21 all facing the same way. The teeth are uniformly spaced and are firmly held in 45 this spaced and aligned relation, until they are finally clamped to the supporting or carrier strip. One arrangement for holding the scoops is shown in Fig. 3, in which the scoops, after having been spaced and aligned by any suitable means, are secured together by spacing members 30 which may be adhesive and serve both to space the teeth and to secure them together. These spacing members 50 may be of a suitable thermoplastic material, which

becomes plastic at reasonably elevated temperatures and hardens at ordinary working or room temperatures. This material may be pressed or poured into a mould containing the teeth and hardened between them. Suitable thermoplastic materials include wax, various metals of low melting point, such as soft solders, and others. Alternatively the teeth may be held together, as shown in Fig. 5, on a comb which includes a backing strip 31 and spacing members 30 between the scoops and integral with the back. This comb may be formed of any suitable thermoplastic material. The material selected for the spacing and holding members is so chosen that it is readily removable from the scoops after the latter have been clamped to the flexible supporting strip. For example if wax is used it may be removed by flexing the stringer to cause the wax particles to drop off, or by brushing with a stiff brush.

20 Metal can be removed by warming and brushing. The scoops are assembled on the backing strip in any desired length and may be easily broken apart or cut off to obtain the exact length which it is desired to make any particular fastener.

25 This assembly of scoops is then placed on the edge of the article to be fastened, as indicated in Fig. 3 and the prongs are clamped about the edges of the article by the press 11, shown in Fig. 7. This supporting strip may either be the tape, as shown

30 in Fig. 1, or it may be the edge of a garment itself. The edge is preferably beaded, as by hemming, rolling, or the like, or as shown in Fig. 3 by sewing a cord 25 to one or both sides of the edge of the fabric. After being removed from

35 the press, the bonding material or backing strip is removed in any suitable manner, as by flexing the carrier strip or by taking off the backing strip, according to what method of assembly has been employed. This results in a completed fastener stringer, as shown in Fig. 1. The two stringers are then joined together by the well known slider, and the stops are placed at the ends of the lines of scoops.

40 While I have shown and described in this application one embodiment which my invention may assume in practice, it will be understood that this embodiment is merely for the purposes of illustration and description and that various other forms may be devised within the scope of my invention as defined in the following claims.

What I claim as my invention is:

1. An elongated strip containing a series of slide fastener members each having open jaws at one end and an interlocking head at the other end, comprising a projection on one side and a recess on the opposite side, said fastener members being arranged in proper relative angular positions and proper spacing for attachment to a slide fastener stringer, and moldable material between the head portions of said fastener members and filling the space around said projections and recesses, said moldable material being removable by heat after said fastener elements have been attached to a fastener stringer.

2. As an article of commerce, a freely trans- 15 portable light weight elongated strip containing a series of slide fastener members each having attachment means at one end, and an interlocking head at the other end comprising a projection on one side and a recess on the opposite 20 side of each member, said fastener members being arranged on the transportable strip in proper relative angular positions and proper spacing for attachment to a slide fastener stringer, and temporary connecting and holding means for holding 25 said fastener members in such positions, said holding means being adapted to be dispensed with after said fastener members have been attached to the stringer.

3. As an article of commerce, a freely trans- 30 portable light weight elongated strip containing a series of slide fastener members each having jaws at one end, and an interlocking head at the other end comprising a projection on one side and a recess on the opposite side of each member, 35 said fastener members being arranged on the transportable strip in proper relative angular positions and proper spacing for attachment to a slide fastener stringer, and temporary connecting and holding means for holding said fastener members in such positions, said holding means being adapted to be dispensed with after said fastener members have been attached to the stringer, said holding means having portions integral therewith extending between the head portions of the fastener members and interengaged 40 with said projections and recesses.

GEORGE HENRY CLIFFORD CORNER.
